UNITED STATES PATENT OFFICE.

DANIEL W. THOMPSON, OF WILMINGTON, OHIO.

RAILROAD-TIE.

1,205,820.

Specification of Letters Patent. Patented Nov. 21, 1916.

Application filed June 15, 1914. Serial No. 845,299.

To all whom it may concern:

Be it known that I, DANIEL W. THOMPSON, a citizen of the United States, residing at Wilmington, in the county of Clinton 5 and State of Ohio, have invented certain new and useful Improvements in Railroad-Ties, of which the following is a specification.

My invention relates to improvements in railroad ties and has for its primary object 10 to provide a tie that is simple as to construction and which will operate to support the rails in a reliable manner and also hold them against creeping or spreading.

An object of importance is to provide a 15 tie that is formed of similar sections that are oppositely disposed and reversely arranged and also united to provide the tie, said sections being formed in such manner that the 20 rails are securely clamped upon the tie, each section carrying integral rail clamping jaws or members.

Another object is to provide a device of 25 the character described that is of simple construction, dispenses with the separate fastening means usually employed to secure rails upon the ties and which is inexpensive to manufacture and install, the sections being capable of shipment in large numbers irrespective of their relative arrangement 30 when assembled.

The above and additional objects are accomplished by such means as are illustrated 35 in the accompanying drawings, described in the following specification and then more particularly pointed out as claimed.

With reference to the drawings, wherein I 40 have illustrated the preferred embodiment of my invention as it is reduced to practice, and throughout the several views of which similar reference numerals designate corresponding parts, Figure 1 is a top plan view of my improved tie showing the same in assembled position, Fig. 2 is a side elevation 45 of the tie in assembled position with the rails removed, Fig. 3 is a transverse sectional view taken on line 3—3 of Fig. 2 showing the sections secured to each other, and Fig. 4 is an end elevation of the sections showing 50 them in position prior to the uniting thereof.

Referring to the drawings by characters of reference, the numerals 1 and 2 designate as entireties longitudinal tie sections that are identical as to construction and designed 55 to be secured in such manner that a tie is

provided and rails securely clamped and supported.

Each tie section 1 and 2 consists of a body 3 which is trapezoidal in cross section, to provide a horizontal base 4 and upwardly and inwardly inclined outer and inner sides 5 and 6 respectively. Near one of its ends each tie section is recessed to provide a rail seat 9, and an outer clamping jaw 9^a. This jaw has a beveled rail base engaging face 10, 65 which overhangs the rail seat 9. This beveled face terminates short of the seat to provide an outer shoulder 10^a at the juncture of the face and seat. An inner shoulder 10^b is formed at the opposite end of the seat. To 70 permit the rail base to be placed upon the seat 9 beneath the beveled face 10, and in engagement with the shoulders 10^a and 10^b, the adjacent end of the central portion 11 of the tie section is beveled as at 10^c. This 75 beveled end terminates at a point above the seat 9 to provide the shoulder 10^b. The seat 9 and beveled face 10 are inclined downwardly in the direction of the outer side 5 of the tie sections. The other end of each 80 tie section is reduced to provide a rail seat 10^d and an inner clamping jaw 10. This jaw is provided with a beveled rail engaging face 10^e which overlies the base 10^d and terminates short of the base to provide an inner 85 shoulder 10^f. This seat and beveled face are also inclined in the direction of the outer side 5 of the tie sections. The upper side of the outer portion of the end of the tie section 90 is located in the plane of the seat 10^d.

The tie sections are assembled to position the seat 9 of one section adjacent the seat 10^a of the other section. After the tie sections are applied to the rails so that the inner clamping jaws 10^e engage over the inner portions of the bases of the rails, and the outer clamping jaws 9^a engage over the outer portions of the bases of the rails, the tie sections are moved toward each other to bring the inner sides 6 in abutting relation, after 100 which they are secured together by means of bolts 7 and nuts 8 which engage the tie sections below the rail seats and by the bolts 12 which engage the central portions of the tie sections above the rail seats. As the seats, 105 and as the beveled faces of the clamping jaws incline downwardly in the direction of the outer sides of the tie sections, they are brought into full abutting and firm clamping engagement with the under and upper 110

sides of the rail bases, respectively, when the tie sections are secured together. When the tie sections are secured together, the lower sides 4 of the tie sections are disposed in an upwardly and oppositely inclined direction providing a longitudinally extending central rib on the under sides of the tie which prevents the tie from moving longitudinally of the road bed. The shoulders 10^a, and 10^b, 10 and 10^c engage the rail bases and hold the rails against any lateral movement with relation to the tie.

In practice, I have found that the form of my invention, illustrated in the drawings 15 and referred to in the above description, as the preferred embodiment, is the most efficient and practical; yet realizing that the conditions concurrent with the adoption of my device will necessarily vary, I desire to 20 emphasize the fact that various minor changes in details of construction, proportion and arrangement of parts may be resorted to, when required, without sacrificing any of the advantages of my invention, as 25 set forth.

What is claimed is:—

1. A rail tie comprising duplicate sections, each section having a horizontal base and upwardly and inwardly inclined outer 30 and inner sides, and means securing the tie sections together with their inner sides in abutting relation, and their bases inclined upwardly in opposite directions, said inclined bases providing the tie on its under side with a longitudinally extending rib adapted to prevent the tie from moving longitudinally of the road bed.

2. A rail tie comprising duplicate sections, each section having a horizontal base 40 and upwardly and inwardly inclined outer

and inner sides, a recessed rail seat at one end of each section, an outer clamping jaw at this end provided with a beveled face overlying the seat, a shoulder at each end of the seat, a beveled end on the central portion of the section to facilitate the application of the rail base to the seat, a second rail seat at the other end of the section formed by reducing this end, an inner clamping jaw on the central portion having 45 a beveled face overlying the second seat, an inner shoulder at the juncture of the second seat and the last named beveled face, and means securing the tie sections together with their inner sides in abutting relation, and 50 their bases inclined upwardly in opposite directions, said inclined bases providing the under side of the tie with a longitudinally extending rib adapted to prevent the tie from moving longitudinally of the road bed. 55

3. A rail tie comprising duplicate sections each having a horizontal base and upwardly and inwardly inclined sides, a rail seat at each end of each section, clamping jaws on each section provided with beveled faces overlying the seats, said seats and beveled faces inclining downwardly in the direction of the outer sides, and means securing the tie sections together with their inner sides in abutting relation, the securing of the 60 sections together moving the rail seats and beveled faces into full abutting and firm clamping engagement with the bases of the rails.

In testimony whereof I affix my signature 70 in presence of two witnesses.

DANIEL W. THOMPSON.
